Attest,

UNITED STATES PATENT OFFICE.

FREDRICK J. FOILL, OF JACKSON, MICHIGAN.

CUSHION-SEAT.

1,140,873.

Specification of Letters Patent. Patented May 25, 1915.

Application filed January 27, 1914. Serial No. 814,782.

To all whom it may concern:

Be it known that I, FREDRICK J. FOILL, a citizen of the United States, residing at Jackson, in the county of Jackson and State 5 of Michigan, have invented new and useful Improvements in Cushion-Seats, of which the following is a specification.

The invention relates to honeycomb cushion seats, and more particularly to the class 10 of spring seats.

The primary object of the invention is the provision of a seat wherein the springs thereof are confined within a honeycomb-like housing affording open pockets for the 15 respective springs so as to prevent the same from becoming disarranged or interfering with each other when being compressed or expanding, thereby assuring perfect resiliency to the seat.

Another object of the invention is the provision of a seat wherein the springs thereof are nested in a novel manner to sustain the same in proper working position.

A further object of the invention is the provision of a seat which is simple in construction, reliable and efficient in its purpose, strong, durable, and inexpensive in manufacture.

With these and other objects in view, the 30 invention consists in the construction, combination and arrangement of parts as will be hereinafter fully described, illustrated in the accompanying drawing, and pointed out in the claim hereunto appended.

In the drawing:—Figure 1 is a side view of the spring structure of a seat constructed in accordance with the invention, with the cover removed. Fig. 2 is a top plan view thereof. Fig. 3 is a vertical longitudinal 40 sectional view through the same. Fig. 4 is a fragmentary horizontal sectional view.

Similar reference characters indicate corresponding parts throughout the several views in the drawing.

Referring to the drawing in detail, the seat comprises spaced upper and lower similar substantially rectangular-shaped frames 5 and 6 respectively, each of which is preferably formed from a rigid rod, and these 50 frames have arranged therein vertically disposed helical springs 7 which are positioned in parallel rows, each spring being of the usual construction, and are connected together by means of tie wires 8 which are fastened at their ends to the frames as shown.

The springs 7 are confined within open cells or pockets 9 formed from opposed flexible strips 10, preferably made from canvas, although they may be made from any other suitable fabric. The strips 10 are stitched together as at 11 transversely thereof to provide the individual open cells or pockets for receiving the springs 7 so that they will be nested and held in separated relation to each other to permit the compressing thereof or 60 expanding of the same without interference with each other.

The open cells or pockets 9 are open at their ends to permit of the insertion of auxiliary springs, (not shown), within the 70 springs 7, should the occasion require, resultant from hard usage of the seat, and thereby increase the cushioning quality of the same. The free edges of the pockets are folded over the springs and connected there- 75 with by the tie wires 8 in the manner shown.

Any suitable cover may be employed to inclose the frames and springs, which cover is made in the usual manner. Also, if found desirable, any number of frames can be used 80 to reinforce the seat.

From the foregoing it is thought that the construction of my device will be clearly understood, and therefore a more extended explanation has been omitted.

What is claimed is:—
A seat comprising superimposed rigid frames, springs arranged in parallel rows within the frames, flexible connected pockets receiving said springs, said pockets being 90 open at both ends and having their free edges folded over said springs, tie wires bridging each row of springs at the opposite ends thereof and terminally connected to each of the said frames, and said wires 95 being formed to provide spaced pairs of coils loosely embracing the uppermost convolutions of the adjacent springs at diametrically opposite points for connecting the free edges of the pockets with the springs 100 and to prevent lateral displacement of the latter.

In testimony whereof I affix my signature in presence of two witnesses.

FREDRICK J. FOILL.
